W. KENNEDY

HEATER

Filed May 23, 1923

INVENTOR
Walter Kennedy

BY *Thomas A. Bell*
ATTORNEY

UNITED STATES PATENT OFFICE.

WALTER KENNEDY, OF CLIFF SIDE, NEW JERSEY, ASSIGNOR TO RADIANT HEAT CORPORATION OF AMERICA, OF NEW YORK, N. Y., A CORPORATION OF NEW YORK.

HEATER.

Application filed May 23, 1923. Serial No. 640,810.

My invention relates to improvements in heaters, and more particularly has reference to gas heaters of the home type.

Referring to the accompanying drawings, 5 I have illustrated in Fig. 1 in perspective, parts being broken away, a suitable form of hearth section or attachment for a heater of the class described, showing the application of the burner and other removable parts. 10 Fig. 2 is a cross-section on Fig. 1, and Fig. 3 is a section on the line 3—3 of Fig. 2 looking from left to right thereof.

4 indicates the base or table of the heater, and 5 a suitable channel or recess in which 15 the radiant or blocks of refractory material are removably mounted. 6 indicates a removable channel for the support of the grilles adapted to stand in front of the radiants, and said channel is preferably provided with 20 key-shaped end portions such as 7 adapted to seat within the recess 8 at opposite ends of the table as shown. Between and substantially below the channels 5, 6 are the burner chambers 9 provided with substantially 25 triangular mixing chambers as shown and grids 10 through which the mixture passes to be burnt. 11 indicates the Bunsen burner tube connected to said burner chamber and preferably terminates with a flare end 11' adapted to be seated in the bifurcated or V-shaped member 12 shown to advantage in 30 Fig. 3, a stop member 13 being provided to engage the periphery of the enlarged end 11' for insuring proper positioning of the burner. At the opposite side of the table 35 prongs or lugs 14 extend and are provided with seatings such as 15 or depressions between the enlarged portions 16, 17 and the burner is preferably beveled or rounded 40 as indicated at 18 to engage the seating 15 and is also preferably provided with teats or buttons 19 adapted to bear against the front surface 20 of the channel 5 to further insure the proper positioning of the burner, 45 from all of which it will be seen that the burner may be placed in position as shown without disturbing any parts except the hearth plate or shelf 21 which may then be placed in position, the depending flange 50 22 thereof having cut-away portions such as 23 to clear the Bunsen tube 10 of the burners, said flange 22 serving as a wind guard. The lugs such as 24 project upwardly from the casting or table 4 at op-

posite sides and engage the ends of the 55 hearth shelf to keep the same from shifting from side to side while the lug 25 extending from the under frame of the hearth table 21 engages the inner surface of the manifold or rectangular gas channel 26, thereby preventing the hearth table from moving out 60 from the heater. This hearth table consists preferably of a frame such as 21 provided with transverse connecting members or straps 27 upon which may be secured slabs 65 such as 28 of tile or other suitable material which may be sealed with cement such as 29 or other suitable hermetical binder.

From the foregoing it will be obvious that 70 the shelf or hearth 21 may be conveniently removed, likewise the channel 6 after the grilles have been taken away, and also the spuds 30 which are adapted to be screwed in the gas channel 26 as shown to advantage in 75 Fig. 2.

The grids 10 it will be observed are 80 beveled along the longitudinal sides so that they may be slid into and out of the open mouth at the top of the burner head 9, and when in position may be locked therein by pinching the ends of the walls 31 of the burner mouth as shown. These grids may 85 of course be secured in other ways such as by a pin, and grids with openings of different sizes may be exchanged or replaced to meet different gas quality conditions and in such case the spuds 30 may also be changed such as where the heater is to be used in a community with a gas of different quality requiring a grid with different opening areas, and a spud with a hole of different bore. This makes the heater universally adaptable, 90 foolproof, quickly changed and easily renewable in parts, convenient for shipment and simple for manufacture. 95

Of course it will be understood that various modifications may be made in the construction and arrangement of parts without departing from the spirit of the invention as claimed. 100

I claim:

1. In a heater of the class described, a base section having a removable hearth, a removable grille holder back of the same, and removable burners beneath said hearth. 105
2. In a heater of the class described, a hearth section having a removable shelf, a removable grille holder back of the same,

and removable burners beneath said shelf, and in combination therewith positioning means for insuring the proper location of each of said burners.

5. 3. In a heater of the class described, a base section having an open portion in which burners may be seated, each of said burners comprising a tube spanning said open portion, and a burner head at one end of said 10 tube, said burner head having a removable grid in the upper end of the burner head connected to said tube.

4. In a heater of the class described, a hearth section having an open portion in 15 which burners may be seated, each of said burners comprising a tube spanning said open portion, and a burner head at one end of said tube, said burner head having a removable grid in the upper end of the burner 20 head connected to said tube, a manifold adjacent the other end of said tube and removable spuds projecting therefrom adjacent said other ends of said tubes.

5. In combination with a heater of the 25 class described, a front base member having a substantially central cut-away portion, a removable hearth adapted to be seated there-over, and burners adapted to be removably retained beneath said hearth.

30 6. In combination with a heater of the class described, a front base member having a substantially central cut-away portion, a removable hearth adapted to be seated there-over, and burners adapted to be removably 35 retained beneath said hearth and in combination with said base member means for positioning said burners.

7. In combination with a member of the 40 class described, a front base member having a substantially central cut-away portion, a removable hearth adapted to be seated there-over, and burners adapted to be removably 45 retained beneath said hearth and a removable grille support at the back of said hearth.

45 8. In combination with a heater of the class described, a front base member having a substantially central cut-away portion, a removable hearth adapted to be seated there-over, and burners adapted to be removably 50 retained beneath said hearth and a radiant support upon said base member behind said hearth.

9. In combination with a heater of the class described, a front base member having

a substantially central cut-away portion, a removable hearth adapted to be seated there-over, and burners beneath said hearth, said hearth having a wind guard.

10. In combination with a heater of the class described, a front base member having 60 a substantially central open portion, a removable hearth adapted to be seated there-over, burners beneath said hearth, and a wind guard between the tube openings and heads of said burners. 65

11. In combination with a heater of the class described, a front base member having a substantially central cut-away portion, a removable hearth adapted to be seated there-over, a fuel manifold in front of said base 70 member, and burners across said cut-away portion.

12. In a heater of the class described, burners extending fore and aft of the same and in front of the radiants thereof, and 75 means in combination with the frame-work of said heater and independently of said burners for positioning the same.

13. In a heater of the class described, a base section having a removable hearth, a 80 grille holder back of the same, and removable burners beneath said hearth.

14. In a heater of the class described, a base section having a removable hearth, a grille holder back of the same, and burners 85 beneath said hearth.

15. In a heater of the class described, a base section having an open portion in which burners may be seated, each of said 90 burners comprising a tube and a burner head at one end of said tube, said burner head having a removable grid in the upper end of the burner head connected to said tube.

16. In a heater of the class described, a hearth section having an open portion in 95 which burners may be seated, each of said burners comprising a tube and a burner head at one end of said tube, said burner head having a removable grid in the upper end of the burner head connected to said tube, a manifold adjacent the other end of said tube and removable spuds projecting therefrom adjacent said other ends of said tubes. 100

In testimony whereof I hereunto affix my 105 signature.

WALTER KENNEDY.
